United States Patent Office

Des. 186,697
Patented Nov. 17, 1959

186,697

AUDIO-VISUAL APPARATUS

Charles J. Beggy, Tucson, Ariz., assignor to Hughes Aircraft Company, Culver City, Calif., a corporation of Delaware

Application December 10, 1958, Serial No. 53,721

Term of patent 14 years

(Cl. D61—1)

FIG. 1.

FIG. 2.

FIG. 3.

FIG. 4.

Figure 1 is a front elevational view of an audio-visual apparatus showing my new design;

Fig. 2 is a top plan view thereof;

Fig. 3 is a right side elevational view thereof; and

Fig. 4 is a left side elevational view thereof.

I claim:

The ornamental design for an audio-visual apparatus, as shown.
